UNITED STATES PATENT OFFICE.

JOSEPH C. EVERSON, OF COLFAX, WISCONSIN.

SAND-SIFTER.

1,084,323.

Specification of Letters Patent. Patented Jan. 13, 1914.

Application filed January 26, 1912. Serial No. 673,703.

To all whom it may concern:

Be it known that I, JOSEPH C. EVERSON, a citizen of the United States, and a resident of Colfax, in the county of Dunn and State 5 of Wisconsin, have invented certain new and useful Improvements in Sand-Sifters, of which the following is a specification, reference being had to the accompanying drawings.

10 This invention has relation to certain new and useful improvements in portable sand sifters; and the object of my invention is to provide a wheel supported device of this general character, of a compact and durable 15 construction which may be drawn to the point of loading to receive the sand and then to the point of delivery to discharge the sand in sifted condition, and my invention includes a frame carrying shell having a 20 screen bottom and a set of agitating blades to stir up the sand, which drops upon a curved shield forming a chute in one position and serving as a door to close the bottom of the shell, the stones and other tailings being arranged to pass out of the rear 25 of the shell.

With these and other objects in view the present invention consists in the combination and arrangement of parts as will be 30 hereinafter more fully described and finally pointed out in the appended claim, it being further understood that changes in the specific structure shown and described may be made within the scope of the claim, without 35 departing from the spirit of the invention.

In the accompanying drawings forming a part of this specification and in which like numerals of reference indicate similar parts in the several views: Figure 1, shows a side 40 elevational view with parts broken away of a sand sifter including my invention. Fig. 2, is a central sectional view with parts broken away. Fig. 3, is a section on line 3, 3, Fig. 2, looking in the direction of the 45 arrow. Fig. 4, shows a rear view.

In my present invention I provide a sand sifter and cleaner which may be used as a vehicle in hauling sand from a certain point and then being drawn to the delivering 50 point where the sand is sifted while being unloaded. The cleaner is, however, primarily intended to be used as a sifter and is arranged to be brought into power connection with an engine or other driving means, 55 whereby the agitating blades may be actuated in sifting the sand.

In the drawings the numerals 1 and 2 designate the base and end sills, and the numerals 3, 4, 5, and 6, the uprights supporting the top bars 7, 8 and 9. In addition, I employ the two spaced transversely held supporting bars 10 and 11, these bars being clearly shown in Fig. 2.

Held between the uprights 3 is the seat 12, which is braced by means of the bars 13 and 14, this construction being shown in Fig. 2.

Secured to the transverse supporting bars 10 and 11, are the bearings 1' and 2', and revolvably held within these bearings is the 70 driven shaft 3', which at its forward end carries the belt pulley 4'.

Held to the forward transverse member 2, as shown in Fig. 2, is the bolster 5', to which is secured the axle 10', the axle being held 75 to the frame by means of the king pin 17.

Secured to the rear of the machine is the axle 18. As shown, the axles 10' and 18 are provided with the wheels 19 and 20, so that this frame may be readily transported.

Secured within the frame, as described, is a frusto-conical shell made of sheet metal including the frusto-conical member 20 having the forward end 21 and the rear end 22. As shown, the largest end of the frusto- 85 conical shell extends toward the rear. The driven shaft 3' passes through suitable openings within the ends 21 and 22 and is held within the bearings 1' and 2', as clearly 90 shown in Fig. 2.

The frusto-conical shell 20 has an opening within the bottom extending the full length of the shell, and covering this opening is a screen 25. Within the rear the member 22, as shown in Fig. 4, is provided with an aperture 26, this aperture being clearly shown in Fig. 4, and closing this aperture is the end gate 27, hingedly secured to the shell as shown in Fig. 2. This gate 27 has an ear 28 arranged for co-action with the ear 29, 100 these ears 28 and 29 being apertured to receive a suitable securing pin 30. When the gate 27 is closed, the aperture 26 within the rear of the shell is securely closed.

Pivotedly held upon a bar 31 secured to 105 the rear bolster 2 of the frame, as shown in Fig. 2, is the recurved end 33 of the curved shield 34, this shield serving as a chute when arranged in one position and closing upon said screen to form a sand tight connection 110 with the shell in its remaining position. As shown in Fig. 1, the shield is provided with

the ears 35 carrying the hooks 36, which by means of a turn buckle 37 is secured to the hook 38 arranged to engage the ears 39 secured to the shell 20, and the ears 40 secured to the hopper, these last mentioned ears being engaged when the shield is closed against the shell. By means of the turn buckle 37, the shield can be so adjusted as to be securely held against the bottom of the shell. This is essential, as in drawing the device over rough ground with a load of sand, the sand would jolt out of the shell if the shield were not securely held to the same.

15 Fastened to the shaft 3, by any suitable means are the hubs 41, from which radiate the arms 42, these arms carrying the agitating blades 43, more clearly shown in Fig. 3. As disclosed, these blades 43 are arranged to 20 pass over the screen 25.

In the use of the sifter, the shaft 3' is suitably actuated, in that a driving belt may be passed over the pulley 4'. The shield 34 is then set in a slanting position, as shown 25 in Fig. 1, being held by the adjustable hooks. The rear gate 27 is opened, in which position the same is also held slanting, but slanting in a direction opposite to the shield 34. Now, on rotating the blades 43, the sand above the 30 screen is agitated which results in the sand sifting through the screen upon the shield 34 and shooting down the same, the stones and other coarse matter, however, passing toward the rear of the frusto-conical shell 35 and tail over the gate 27, so that the sand

may be collected in one pile and the coarse tailings in a separate pile.

The device is simple of construction and positive of operation.

It is of course understood that if desired 49 a gasolene or other engine could be secured directly to the frame.

Having thus described my said invention, what I claim as new and desire to secure by 45 United States Letters Patent is:—

The combination with a portable frame, of a frusto-conical shell secured within said frame having an opening within the bottom extending the full length of the shell, a hopper entering the smallest end of said 50 shell from above, an aperture being provided within the largest end of said shell near the bottom, a hinged gate closing said aperture, a screen covering said bottom opening, a curved shield serving as a chute pivotally 55 secured at one end to the largest end of said shell, ears secured to said shell, adjustable hooks carried by said shield to engage said ears, said shield closing upon said screen in one position, a driven shaft passing through 60 said shell, arms extending from said shaft, and agitating blades secured to said arms arranged to pass over said screen, all arranged as and for the purpose set forth.

In testimony whereof I affix my signature, 65 in presence of two witnesses.

JOSEPH C. EVERSON.
